United States Patent Office

Des. 188,447
Patented July 19, 1960

188,447

SECTIONAL COUNTER FOR TELLERS OR THE LIKE

Francis C. Kegel, North Tonawanda, N.Y. (238 Fern-
dale Ave., Kenmore, N.Y.), and Joseph L. Homes-
berger, 153 Ralston Ave., Kenmore, N.Y.

Filed Oct. 23, 1959, Ser. No. 58,044

Term of patent 14 years

(Cl. D80—2)

Fig. 1.

Fig. 2.

Fig. 3.

Fig. 4.

Fig. 5.

Fig. 6.

Fig. 7.

Fig. 8.

Fig. 1 is a front elevational view of a sectional counter for tellers or the like embodying our new design.

Fig. 2 is a top plan view thereof.

Fig. 3 is a rear elevational view thereof.

Fig. 4 is a bottom plan view thereof.

Fig. 5 is a right end elevation view thereof.

Fig. 6 is a left end elevational view thereof.

Fig. 7 is a vertical cross-sectional view thereof taken on line 7-7 of Fig. 3.

Fig. 8 is a vertical cross-sectional view thereof taken on line 8-8 of Fig. 3.

We claim:

The ornamental design for a sectional counter for tellers or the like, substantially as shown.
